EDGAR F. HATHAWAY AND CHARLES LEA, OF BOSTON, MASSACHUSETTS, ASSIGNEES,
BY MESNE ASSIGNMENTS, TO BARBER-COLMAN COMPANY, OF ROCKFORD, ILLINOIS, A CORPORATION OF ILLINOIS.

WARP-REPLENISHING MECHANISM.

1,339,507.

Specification of Letters Patent. Patented May 11, 1920.

Application filed March 21, 1910. Serial No. 550,597.

To all whom it may concern:

Be it known that we, EDGAR F. HATHAWAY and CHARLES LEA, both citizens of the United States, and residents of Boston, county of Suffolk, and State of Massachusetts, have invented an Improvement in Warp-Replenishing Mechanism, of which the following description, in connection with the accompanying drawings, is a specification, like letters on the drawings representing like parts.

This invention relates to improvements in warp replenishing mechanisms, being more particularly intended to provide means for facilitating the preparation of warps for installation in the loom.

While the invention may be embodied in widely different forms and certain of its features may be usefully employed in connection with warp replenishing machines other than those of the drawing-in type, herein, for illustrative purposes, we have shown one embodiment thereof in the form of a transfer apparatus for use in conjunction with warp drawing-in machines, such apparatus being adapted to load or unload the machine with the warp, harnesses or other loom elements employed, and being of such a nature as to increase the capacity and output of such machines, and facilitate the work of drawing in the warps thereon.

Our invention will be best understood by reference to the following description when taken in connection with the accompanying illustration of one specific embodiment thereof, while its scope will be more particularly pointed out in the appended claims.

Referring to the drawings:

Figure 1 is an end elevation partly broken away showing a portion of a drawing-in machine with a transfer device shown in coöperative relation thereto;

Fig. 2 is a plan view of the transfer device with the warp beam only in place thereon;

Fig. 3 is a side elevation of the same device showing the drawn-in warp together with the reed, five harnesses and two sets of drop bars all supported by the said device;

Fig. 4 is a front elevation of the transfer

device with the warp beam thereon, as shown in Fig. 2;

Fig. 5 is a plan view of the warp drawing-in machine and the transfer device as shown in Fig. 1, but shown on a smaller scale;

Fig. 6 is a detail partly in section showing the relation of one of the harness positioning devices to the individual eyes of a small section of the harness;

Fig. 7 is an end view; and Fig. 8 a sectional view of the clutching and driving device for the harness separator device shown in Fig. 6;

Fig. 9 shows in front elevation a short section of a harness with upper and lower harness shafts and the harness eye positioning device in engagement with the heddles;

Fig. 10 is a side elevation showing in part a modified form of harness and reed holding device for the transfer apparatus;

Fig. 11 is a section in elevation on the line 11—11 in Fig. 10;

Fig. 12 is a front elevation of another form of harness holder for the transfer device;

Fig. 13 is a side elevation of the modification shown in Fig. 12; and

Fig. 14 shows still another modified form of harness holder.

Referring to the drawings and to the embodiment of the invention by which we have therein illustrated the same, we have shown one form of transfer, or loading or unloading, device coöperatively associated, by way of example, with a well known type of drawing-in machine 1, the latter being of the same general construction as that shown in Patents 755,861 to Field, 871,680 to Field *et al.*, and 862,474 to Hathaway. Such machine is herein shown, for the sake of illustration, it being obvious that the transfer device described may, with suitable modification, be usefully employed both with warp drawing and other machines of widely different construction.

In the illustrated form of machine, as is well known, to those skilled in the art, the weaving elements, that is to say, the warp threads and those elements, such as the harnesses, reed and drop wires, which

- accompany and are associated with the drawn-in warp for the control thereof in the loom, are supported in a generally parallel arrangement lengthwise the machine, 5 while an appropriate needle 2 (see Fig. 5) or other thread placing device, carried by the traveling carriage 3 is caused to traverse the extent of the reed and harnesses and place successive warp threads through 10 the desired heddle eyes and the selected reed dents, these being appropriately positioned for that purpose in the needle path by suitable selecting and positioning mechanisms.
- 15 In this, or in any other type of drawing-in machine, much time is usually expended in installing the loom elements in the machine preparatory to the drawing-in operation, and much time is apt to be expended in disconnecting and removing the drawn-in warp and other weaving elements from the machine after the drawing-in operation, as well as in checking up errors in the placing 20 of the threads and correcting such errors 25 when they are found to have occurred. In the described form of machine selecting and positioning devices are employed for the harnesses which must be carefully applied to the harnesses when the latter are installed 30 in the machine, and carefully removed therefrom when the harnesses are withdrawn.
- To reduce the period of idleness or inaction thus forced upon the machine, we have provided (as shown in Fig. 1) for use co- 35 operatively with the drawing-in machine, a movable transfer device 4 which is adapted to present the loom elements for installation in the drawing-in machine in substantially the same general relation they are to 40 occupy therein, so that they may be conveyed to the machine, installed therein, and thereafter withdrawn from the machine after the drawing-in operation has been completed. Through the provision of two 45 or more of such transfer devices it is possible during the drawing in of one warp to correct and check simultaneously the previously drawn-in warp while the latter is sustained upon one of these handling and 50 conveying devices and to make such other preparations for the installation of the warp harness or reed in the loom as are now made while those elements remain supported in the drawing-in machine. At the same time 55 a warp may be made ready for installation in the machine as soon as the warp then in the machine is drawn in, this being accomplished by arranging the loom elements upon another loading device in the relation 60 they are to occupy in the machine and applying to the harnesses those portions of the separating and positioning mechanisms which are detachable from the drawing in machine. In this manner the drawing-in 65 machine can be kept in substantially con-

tinuous operation without those prolonged interruptions which have heretofore been necessary in installing the undrawn warp in the machine and taking the drawn-in warp therefrom.

70 Referring to the particular type of warp handling device illustrated, the same comprises a frame work consisting of end frame members 5 and 6, suitably united by longitudinal tie rods 7 and so mounted as to be 75 readily conveyed from one point to another, as upon the roller casters 8 of any suitable construction.

75 Referring first to the means for supporting and handling the warp beam, near the 80 lower part of the holder there is provided means for sustaining a warp beam. Such beam sustaining means may be provided in various ways, but herein one of the frame members 5 has a concave pocket 9 in its upper end which pocket is adapted to receive one end of the pintle or shaft 10 for the warp beam 11. The opposite end of the warp beam shaft rests in a similar pocket 85 formed in an intermediate frame member 12 (Figs. 2 and 4) the latter being adjustable lengthwise the tie rods 7 so as to accommodate different lengths of warps and warp beams.

80 The warp beam when placed in the loading device preparatory to installation in the machine will occupy the position shown in Fig. 1, the ends of the warp threads being secured by the clamp 13 fastened to the edge of the beam.

85 When it is desired to install the warp (together with the other weaving elements) in the machine the loading device is pushed along the floor of the mill to the front side of the drawing-in machine, as indicated in 90 Fig. 1. To receive the warp beam suitable stationary beam-holding means are provided at the machine, the same herein comprising the supports 14 having the beam receiving pockets 15. The supports are so positioned as to project out from the base of the machine to be closely adjacent and in registration with the pockets 9 on the frame members 5 and 12 when the loading device 95 is finally positioned at the machine.

100 The supports 14 rest upon the channel iron 16 and the T-iron members 17 and 18 (see Fig. 2 in dotted lines) both occupying a fixed position relatively to the drawing-in machine. The supports are adjustable 110 along the members 16 and 17, while securely held thereon, such adjustable attachment being herein had by providing a shouldered part 19 on each support underlying the upper lip of the channel iron 16. The 115 T-irons 17 and 18 also provide a positioning means for the loading mechanism, the frame members 5 and 6 being provided with projections 20 and 21, respectively, which are pushed up against the T-iron when the 120 125 130

loading device is positioned, thereby insuring repeatedly the same and the correct position of the various parts of the loading device in a transverse relation to the drawing-in machine. The correct position of the loading device longitudinally the drawing-in machine is insured by the contact of the projection 20 on the frame member 5 with the upright part of an angle iron 22 (see Figs. 2 and 5) located at one end of the T-iron 18.

When the loading device has been pushed into the proper position as described, the frame members 5 and 12 are brought into registration with the supports 14 and the warp beam can then be displaced from the pockets 9 on the loader into the pockets 15 on the stationary machine supports. This may be accomplished by any suitable means, but herein there are provided a pair of lifting devices 23, each in the form of a U-shaped bracket, which are adapted to be elevated by the foot treadle 24 under the ends of the warp beam shaft, so that the latter is lifted out of the pockets 9. The warp beam can then be manually rolled along the brackets over the stationary pockets 15 and dropped therein by releasing the foot treadle. Each bracket is carried by a vertical plunger rod 25 adapted to be raised or lowered by rocker arms 26, the rocker arms being connected each to the squared shaft 27, the latter having the foot treadle 24 directly connected thereto. The plunger rods 25 are guided in bearings 28 attached to the frame members 5 and 12, so that the bracket next adjacent the frame member 12 is adjustable with the latter lengthwise the holder.

Referring now to devices for supporting the harnesses, reed and other loom elements to be installed, the loading device is provided with upright supports herein in the form of rods 29, held one in each frame member 5 and 6, such supports carrying each one or more supporting arms on which the various loom elements can be arranged in substantially the relation they are to occupy or have occupied in the drawing-in machine. In the embodiment of the invention shown in Figs. 1 and 5, inclusive, there are provided at each end of the apparatus upper and lower supporting arms 30 and 31 respectively. Each arm 30 is mounted for horizontal transverse sliding adjustment in a holder 32, there being provided a set screw 33 to fix the adjusted position of the arm. The holder 32 in turn is mounted for longitudinal adjustment along the supporting rod 34, the latter preferably having a square or other noncircular cross section. The rod 34 in turn is sustained at each end by a bracket or hanger 35 secured to the upright support 29 such as to permit vertical adjustment as by the adjusting screw 36.

Each supporting arm is preferably grooved (see Fig. 14) or otherwise provided with positioning means for the harness shafts so that harnesses, to the required number, may be hung upon the supporting arms 70 in the required relation, and, if desired, positioning devices may also be employed for the supporting bars of one or more sets of drop wires, as indicated in Fig. 3. It will be seen that the harness supporting arms 75 have all required adjustments for variations in the height and spread and the number of the harnesses, as may be required for use in connection with any particular drawing-in machine.

In the loading apparatus shown in Fig. 1, a lower supporting bar 31 is also provided for maintaining the spread of the harnesses and facilitating their installation in and withdrawal from the machine. The two 85 lower supporting arms 31 are mounted in holders 37 carried by the transverse rod 38, the latter sustained by the hangers 39, these several parts being adjustable in substantially the same fashion as the supporting 90 parts for the arms 30.

The lower supporting arm 31 (as shown in Fig. 3) may also be grooved at 40, or otherwise fashioned to provide a support for the reed 41 when the latter is withdrawn 95 from the machine with the drawn-in warp. The loader may be arranged to hold the reed in the desired relation with reference to the harnesses when the latter are applied to the machine for installation therein, or the reed 100 may be manually and separately installed in the machine irrespective of the loading device, it being ordinarily a simple and quick matter to apply the reed to the reed holder 105 of the machine.

In making use of the described loading mechanism when it is desired to equip the same with loom elements for installation in the machine, the warp beam with the undrawn warp thereon is placed in the warp 110 holding pockets. The harnesses are then hung upon the supporting arms 30 and 31 in the positions represented in Figs. 1 and 3, and the harness separating devices, if the latter are detachable from the drawing-in 115 machine, and require adjustment to the harnesses prior to the drawing-in operation, are then applied to the several harnesses.

In the described form of machine (see Figs. 6 and 9) the heddles are separated by 120 the coils of a helical spring 42, (as described in the aforesaid Patent #775,861). It is customary to apply these each as a permanent attachment to its harness, a cord 43 (see dotted line, Fig. 9) being drawn 125 through the coil to keep the heddles in place in the spring when the harness is in the loom. When the harness is used in the loom (see patent to Lanning, #795,989) a rod 44 is inserted through the spring 42 and holds 130

the latter near the underside of the upper harness shaft by means of the cord 43, out of line of the warp threads in the shedding operation. When preparing for the drawing-in operation, the spring 42 is moved to the position shown by full lines in Fig. 9, and the separating cord 43 replaced by the separator shaft 45, which carries the coarse pitch worm 46, the latter engaging the coils 10 of the spring so that, when appropriately turned, the worm will act to separate and position the heddles and the heddle eyes (see Figs. 6 and 9).

The application of the detachable separating devices in the case of each harness, consisting in the substitution of the separator worm shaft for the cord 43, has heretofore been performed after the harnesses have been placed in the drawing-in machine. 15 This operation, however, can be performed with equally or greater facility after the harnesses have been hung in position on the loading mechanism as described, and prior to their installation in the machine, thereby 20 materially reducing the period of time during which the machine is idle.

The same is true of the operation of raising the separator spring and fastening it in the position shown in dotted lines (Fig. 9) 30 after the drawing-in operation. This, as well as the checking and correcting operation also can be performed with equal or greater facility on the unloading device than in the machine.

35 With the loom elements installed in the loading machine and the harness separating devices applied thereto, the loading device may be then moved from the position where the preparatory operation has been carried 40 on to the drawing-in machine and positioned as represented in Fig. 1. The warp beam is then transferred to the fixed supports 14, as previously described. The harnesses which have been brought into substantially 45 the position they are designed to occupy in the drawing-in machine can then be secured thereto by attaching to the upper harness shafts the harness supporting members 47. In the described form of machine these comprise hook supports having each a spring or other connection 48 and depending each from a rod 49 resting upon suitable roller supports 50 carried by the machine frame. The upper harness shaft of each harness 55 having been attached to its spring supported hook and the lower harness shaft to a suitable stretching device such as the depending weight 51 and the reed 41 having been presented to its holder either by the 60 loading mechanism or independently thereof, the entire loading frame can be moved back out of the way and entirely free from the machine.

If drop bars are employed, they can be 65 suspended upon suitable hanger bars rest-

ing on the supporting arm 30 and placed in their respective supports in the drawing-in machine.

After withdrawal of the machine, the warp can be applied to the warp clamps in the usual manner, assuming the position represented by dotted lines in Fig. 1.

After the drawing-in operation has been performed an empty loading frame can be pushed up into the position shown in Fig. 7 1. The warp beam can then be transferred from the fixed supports 14 to the beam holding pockets on the holder by pressing down upon the foot treadle 24 and the harnesses and drop bars can be transferred to the 80 loader by merely detaching them from their supports on the warp drawing machine. The ends of the drawn-in threads are knotted together outside the reed so as to prevent escape therefrom, and the latter is 85 placed in the holding pockets provided on the lower arms 31 as represented in Fig. 3. With the parts in this position the transfer frame can then be withdrawn from the machine and the drawn-in warp and loom elements, appearing as shown in Fig. 3, can be 90 conveyed to that part of the room or mill where the checking and correcting operation is to be carried on and where the harnesses are to be prepared for the loom. The 95 installation of a new warp to be drawn in, as first described, can follow immediately the withdrawal of the drawn-in warp, so that the interval between successive drawing-in operations on the machine is reduced 10 to a minimum.

If desired, the transfer device may be provided with means for holding a warp thread clamp, such as the clamp 52, which clamps the warp when in the machine between the 105 warp beam and the separating mechanism.

Such holding means are herein provided in the form of slightly inclined brackets or hangers 71 adjustably secured one over each end of the warp beam on the square sectioned supporting rod 38. Each hanger is provided with the hinged latch 72 which can be thrown down to hold the clamp in the hanger as seen in Fig. 3. When the transfer device is moved into position for the 115 withdrawal of the drawn-in warp from the drawing-in machine the latch 72 is thrown back out of the way and each hanger assumes a position under the end of the clamp 52 seen in Fig. 1. After the warp beam has 120 been transferred to the transfer device, the pivoted latches are thrown down, thereby securing the clamp to the unloading mechanism so that the warp is removed with the threads clamped just as they stood in the 125 drawing-in machine. This sometimes facilitates the work of checking up the errors.

When the warp is installed in the machine, the clamp may be carried in the bracket as a convenient holder therefor, or 130

one-half the clamp, that is to say, one of the two members composing the clamp may be left in the drawing-in machine while the other clamp member is carried in the bracket 5 on the transfer device so as to be brought into proximity to its intended position on the drawing-in machine when the loading device is properly positioned at the side of the machine.

- 10 Having reference to the harness eye separating devices, upon the described form of machine (see Figs. 5 to 9, inclusive) each separator shaft is disengageably connected to a suitable driving device upon the machine, such device herein consisting of a socket member 53 in which the end of the shaft is held by the hinged spring-pressed key member 54. The socket member 53 is driven from a driving shaft 55, the latter having a rotatably adjustable connection therewith by means of the crank member 56 and pin 57, which latter can be forced into engagement with any one of a number of holes 58 formed in the inner face of the socket head. The driving shaft 55 is operated at intervals by means of a pattern mechanism (not herein shown) so that separator shafts are intermittently turned in predetermined order so as to present a harness eye from a selected one of the five sets of harnesses employed. The pitch of the separator worm is coarse and the arrangement is such that one-half a revolution of the separator shaft moves the harness eye 30 from the position *a* (see Fig. 9) out of the path into the position *b* (within the needle path) and a second half revolution of the separator shaft moves the said eye into the position *c* (again out of the needle path).
- 40 It will be seen that in the case of the described harness eye separating devices, in addition to the careful application of the separator shaft to the harness and the harness separating spring which must be 45 formed before a drawing-in operation can be carried out, the separator worm must also be carefully adjusted with reference to the driving shaft 55 both as to angular position and distance lengthwise the separator shaft therefor, for upon such angular and longitudinal adjustment depends the exact position at any given time of the particular harness eye or eyes controlled thereby.
- 50 Heretofore, where the harnesses and other elements have been separately installed and prepared in the drawing-in machine itself, but one set of separator shafts has been required and it has been necessary to adjust each shaft with its worm only at the 55 outer set. Where a loading device of the type described is employed and the harnesses are arranged and prepared prior to installation in the drawing-in machine, in order to avoid the necessity for a separate adjustment of 60 each separator shaft after it has been placed

in the machine, thereby considerably delaying the drawing-in operation, it is desirable to employ two or more sets of separator shafts, the shafts and worms of the several sets being interchangeable for any one harness. Our invention, therefore, contemplates the employment, in conjunction with a drawing-in machine and two or more transfer devices, also two or more sets of detachable interchangeable harness positioning devices.

70 In Fig. 10, we have shown a modified form of supporting device for the heddles, whereby the lower supporting arm, if desired, may be dispensed with. Herein the 80 supporting arm 59 is pivoted at 60 upon the upright support 61. The arm 59 may be turned up out of the way about the pivot, but when turned down in the horizontal position, it is there held by the stop pin 62. 85 Carried by the arm is a series of blocks 63, adjacent ones being separated by the spring 64, but adapted to be forced together by the pivoted cam member 65 having the handle 66. The several brackets have each a rubber 90 facing 67. The harnesses may be placed in position upon this support by inserting the upper harness shaft between adjacent blocks and between the rubber facings 67 after 95 which the cam member 65 can be turned to compress the blocks and hold the harnesses fast between the same.

100 This support engages the sides of the harness shafts between the ends thereof and cannot therefore interfere with the spring 42 when the latter is held in the raised position shown in dotted lines in Fig. 9. The end block in the series may be provided with depending clips 68 which may be suitably formed to receive the reed 41. It will be 105 understood that the holder shown in Fig. 10 is duplicated at each end of the latter so that the loom elements can be applied to the machine and withdrawn therefrom as previously described in connection with the loading mechanism in Fig. 1.

110 While the construction shown in Fig. 10 contemplates a series of common gripping members for the several harnesses, individual gripping devices for the harnesses may 115 be employed if desired.

120 In Figs. 12 and 13, we have shown a third modification. Herein, in place of the upper supporting arm 30 at each end of the loading device, there is provided an angle iron 69 on which the end of each upper harness shaft can rest loosely as represented in Fig. 12.

125 If desired the harness supporting arm 30 may have a beveled or pointed end, as shown at 70 in Fig. 14.

130 The gripping devices, such as are shown in Fig. 10, are especially convenient for unloading the loom elements from the drawing-in machine, and, if desired, some such

expedient may be employed for unloading, while the sword shaped or other supporting arms 70 are employed in loading the machine, or the gripping devices or supporting arms alone, as the case may be, may be employed in both loading or unloading.

Our invention is capable of use with suitable modification either as an unloading device exclusively or a loading device exclusively, although the same is herein described as performing both functions.

While we have herein shown and described for purposes of illustration one specific form of the invention, it is to be understood that extensive deviations may be made from the details of construction as well as the arrangement of parts and application made of the invention without departing from the spirit thereof.

20 Claims.

1. In a transfer mechanism for warp replenishing machines, the combination with a warp beam holder of a pair of U-shaped brackets adapted to underlie each end of the warp beam shaft, means for elevating said brackets to lift the warp beam out of the holder, said beam being adapted to roll on the bracket from one position to the other.

2. The combination with a warp drawing machine having means thereon for holding the warp and one or more harnesses in such relation as to permit the threading of the warp through the harness eyes, automatic thread-placing means, and a portable loading or unloading device adapted to transfer the warp and harness to or from the machine, the said device having means for holding the warp and one or more harnesses in the same general relation which they occupy in the loom.

3. The combination with a warp drawing machine of a movable loading or unloading device having a warp beam support, means for transferring the warp beam from one machine to the other and one or more projecting harness supporting members for transference of the harnesses from one machine to the other.

4. The combination with a warp drawing machine of a harness transfer device therefor, the latter comprising harness supporting means for holding the harnesses in a predetermined relation and in a fixed vertical position until released therefrom.

5. The combination with a warp drawing machine of a harness transfer device therefor, the same comprising means for holding in predetermined relation two or more harnesses said holding means engaging said harnesses each about the sides and between the ends of the upper harness shaft.

6. The combination with a warp drawing machine having a harness support, a transfer device having a harness support, and a

plurality of detachable interchangeable harness positioning devices for said machine.

7. The combination with a warp drawing machine having means for supporting one or more harnesses and a plurality of interchangeable detachable harness positioning devices adapted to be substituted one for the other in the machine.

8. The combination with a warp drawing machine having means for supporting one or more harnesses and a plurality of interchangeable harness positioning worms each with its operating shaft adapted to be substituted one for the other in the machine.

9. The combination with a warp drawing machine having means for supporting one or more harnesses of a harness transfer device and a plurality of detachable interchangeable harness positioning devices for each harness.

10. A harness transfer device for a warp drawing machine having a harness support and means for clamping thereon a plurality of harnesses in a predetermined position.

11. A loading or unloading device for warp replenishing machines, comprising a portable warp beam holder, means for holding in a predetermined inter-relation one or more loom harnesses and means to engage the harness shafts and tension the harnesses.

12. The combination with a warp drawing machine of a harness transfer device therefor, the latter comprising harness supporting means for holding the harness in a fixed vertical position, and means for stretching the harness vertically.

13. In a transfer device for a warp drawing machine, the combination with a portable warp beam holder, of a warp beam holder on the machine, transfer mechanism for transferring the warp beam from the portable holder to the stationary holder, or vice versa, and means on the portable holder for carrying the harnesses and a reed in suitable relation to be installed in the machine.

14. A harness transfer device for a warp drawing machine comprising means for holding two or more harnesses, and means for clamping said harnesses in predetermined and separated relation on said transfer device.

15. The combination with a warp drawing machine having means for supporting a plurality of harnesses in parallel but separated relation thereon, harness eye selecting devices, warp thread placing means, and a loading or unloading device comprising a movable support, a warp beam holder and harness supporting means for supporting harnesses thereon in the same general relation which they occupy in the machine.

16. The combination with a warp drawing machine having means for supporting a plurality of harnesses in parallel but

separated relation thereon, harness eye selecting devices, warp thread placing means, and a loading or unloading device comprising a movable support, a warp beam holder and adjustable harness supporting means for supporting harnesses thereon in the same general relation they occupy in the machine.

17. The combination with a warp drawing machine having means for supporting a plurality of harnesses in a generally parallel but separated relation, means for supporting a reed parallel to the harnesses, separating devices for the harnesses and reed, a thread-placing device and a transfer device having a warp beam support and supporting means for the harnesses and reed maintaining them in the same general relation to each other and to the warp beam which 20 they occupy in the warp drawing machine.

18. The combination with a warp drawing machine having means for supporting a plurality of harnesses and one or more banks of drop wires in a generally parallel but separated arrangement, selecting devices for the harnesses and drop wires, a thread placing device and a transfer device having a warp beam support, and means for holding said harnesses and drop wires in the same general relation which they occupy in the warp drawing machine.

19. The combination with a warp-drawing machine having means for supporting one or more harnesses in such relation as 35 to permit the threading of the warp through the harness eyes, of a movable loading or unloading device having harness-supporting means adapted to receive the bars of the individual harnesses directly thereon, said 40 supports being adapted to be brought into coöperative relation to the supporting devices on the machine and permit the transference of the harnesses individually from one machine to the other.

45 20. The combination with a warp-drawing machine having means for supporting a warp and harnesses in such relation as to permit the drawing-in of the warp threads and having also automatic thread-placing 50 means, of a loading or unloading device adapted to transfer the harnesses to or from the machine, said device having means for holding the harnesses in the same general relation to the warp which they occupy 55 in the machine, said harness-holding means being adapted to engage the harness bars and permit the individual transference of the harnesses directly from the bar-holding

devices in the machine to the bar-holding devices in the loading or unloading device. 60

21. The combination with a warp-drawing machine, of a movable loading or unloading device having upright supports and laterally directed harness-supporting members secured thereto, said device being 65 adapted to be placed in such relation to the warp-drawing machine to insert the laterally-extending harness supports over the body of the machine and under the harness-supporting devices therein to permit 70 the individual transference of the harnesses from the machine to the loading or unloading device or vice versa.

22. The combination with a warp-drawing machine, of a movable loading or unloading device having overhanging harness-supporting arms adapted to receive the bars of one or more harnesses, said device being adapted to be moved to bring 75 said arms directly under the harness-supporting devices in the machine and permit the transference of the harnesses from the bars to the supporting devices of the machine or vice versa.

23. A movable loading or unloading device having overhanging harness-supporting arms adapted to receive directly the harness bars of the individual harnesses, said arms being adjustable, so that when 80 said device is moved to insert said arms within the machine, the harness bars may be brought in coöperative relation to the bar-supporting devices on the machine and permit their transference from one to the other and may occupy on said arms substantially the same relation they occupy in 85 the machine.

24. The combination with a warp-drawing machine, of a transfer mechanism therefor, comprising means for withdrawing 100 from the machine the drawn-in warp, the harnesses, and the reed in the same general relation which they occupy in the machine, said mechanism having means to transfer the harnesses individually from the harness-bar holding devices in the machine to harness-bar holding devices on the transfer mechanism. 105

In testimony whereof, we have signed our names to this specification, in the presence 110 of two subscribing witnesses.

EDGAR F. HATHAWAY.
